UNITED STATES PATENT OFFICE.

WILSON D. EDWARDS, OF TERRE HAUTE, INDIANA, ASSIGNOR TO TURNER BROS. COMPANY, OF TERRE HAUTE, INDIANA, A CORPORATION OF INDIANA.

DESIGN FOR A VINEGAR CRUET.

Application filed July 17, 1924. Serial No. 10,176. Term of patent 3½ years.

To all whom it may concern:

Be it known that I, WILSON D. EDWARDS, a citizen of the United States, residing at Terre Haute, in the county of Vigo and State of Indiana, have invented a new, original, and ornamental Design for Vinegar Cruet, of which the following is a specification, reference being had to the accompanying drawing, forming a part thereof.

The figure is a view of a vinegar cruet showing my new design.

I claim:

The ornamental design for a vinegar cruet as shown.

WILSON D. EDWARDS.
